Primary Examiner — Marie D. Fast Horse(74) *Attorney, Agent, or Firm* — Chun-Ming Shih; HDLS IPR Services(57) **CLAIM**

The ornamental design for a wireless receiver, as shown and described.

DESCRIPTION

FIG. 1 is a perspective view of a wireless receiver showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is second perspective view showing the wireless receiver; and,

FIG. 9 is a perspective view showing the wireless receiver in use.

The broken lines in the drawings depict an unclaimed portion of the wireless receiver and form no part of the claimed design.

The unshaded surfaces shown between the solid lines and the broken lines form no part of the claimed design.
